UNITED STATES PATENT OFFICE

JOHN I. BELLAMY, OF BROOKFIELD, ILLINOIS, ASSIGNOR TO RESERVE HOLDING COMPANY, OF KANSAS CITY, MISSOURI, A CORPORATION OF DELAWARE

TELEPHONE SYSTEM

Application filed June 15, 1928, Serial No. 285,530. Renewed May 24, 1930.

The present invention relates to telephone systems in general, that is concerned more particularly with telephone systems using non-numerical switching apparatus; and the main object is the production of new and improved arrangements whereby the operation of the so-called plunger-type secondary, non-numerical line switches is rendered more satisfactory.

10 The present invention has been applied to secondary line switches of the plunger type used in an automatic telephone system between one level of the banks of a group of automatic selectors and a group of trunk lines 15 outgoing to a distant office. In such an arrangement, as is well known, the selectors are divided into sub groups as regards the level in question and each sub group has access to ten trunks extending to secondary line 20 switches in several groups, each secondary line switch group being controlled by a separate master switch and having access to a separate sub group of ten outgoing trunk lines.

25 Although arrangements as outlined above have been employed commercially for many years and have proven highly satisfactory, an outstanding defect has been present. This defect lies in the arrangements provided for rendering the incoming trunks busy to the remaining secondary line switches of a sub group when one of them is seized. The result is that one or more additional line switches are often seized and perhaps operated before the remaining trunks are made busy to the selected switches having access to them. This results in lost calls owing to the fact that two switches often seize the same 30 trunk and owing to the fact that the second connection has often released by the time the master switch finds an idle trunk in case the last seized secondary switch was seized too late to be operated before the battery potential is removed from the so-called "open-main" conductor. This defect becomes more apparent when there is only one idle trunk line accessible to a sub group of line switches. In this case, when another line switch is seized 35 no further calls should be permitted to come

into the secondary group because such line switch takes the last remaining idle trunk.

Keeping in mind the defects outlined above, the specific object of the present invention is the production of suitable circuit 55 arrangements for rendering all the remaining idle trunk lines busy in a secondary sub group when one of them is seized until the seized line switch has operated and the master switch has located a new idle trunk line.

Accordingly, the circuit arrangements have been revised so that the release trunk conductors of all idle trunk lines in a sub group are normally connected together, so that the placing of a ground potential on any one of them seized by a selector renders the entire sub group busy, arrangements being provided for removing the busy condition only after the seized line switch has operated and the master switch has found another idle trunk line. By 60 this arrangement, if the trunk seized is the last idle one in a group, the master switch is unable to find another idle trunk line and the busy condition is maintained on the remaining idle trunk incoming lines until such time 65 as another outgoing trunk line becomes idle and is preselected. It will be understood of course, that while one sub group of trunk lines is busy the calls are routed by the 70 selectors into such other sub groups as may 75 contain idle trunk lines.

Referring now to the drawings comprising Figs. 1 and 2, Fig. 1 shows a trunk line comprising conductors 2, 3, and 4, and leading from the banks of selectors (not shown) to the secondary line switch SLS. The repeater R, which is one of the ten repeaters to which the secondary line switch SLS has access in common with other secondary line switches, is shown interposed between the line switch 80 banks and the outgoing conductors 27 and 28, according to standard practice. A portion of the master switch which presides over the said group containing the secondary line switch SLS has been shown in the lower part 85 of the drawing, as well as the control group of relays common to the sub group of line switches. The secondary line switch is arranged through the cooperation of relays 5 and 6 to reapply ground potential to release- 90 95 100

trunk conductor 3 upon the release of the connection for a short interval so as to maintain the trunk line guarded during the restoration of the plunger arm the realignment of the plunger so as to permit the use of the so-called self aligning plungers, which plungers are immediately returned to the control of the master switch without waiting for the master switch to be advanced to where it will pick them up again.

Fig. 2 shows the secondary line switch SLS' which is the same as the secondary line switch SLS except that it does not contain a relay corresponding to relay 6 and consequently does not have the added guarding feature above mentioned, as it is unnecessary when non-self-aligning plungers are used.

The invention having been described generally, a detailed description of the operation 20 of the apparatus shown will now be given. For this purpose it will be assumed that the master switch is standing in the position shown in the drawing with the trunk line extending to the repeater R preselected and that 25 the idle trunk comprising conductors 2-4 and extending to the secondary line switch SLS is seized by a selector. When the seizure is made, the calling subscriber's loop is extended and placed across conductors 2 and 4 in the usual manner and ground potential is 30 applied by the seizing selector to release-trunk conductor 3. Conductor 3 is normally connected through contacts of relays 5 and 6 to guard conductor 39, which is common, as indicated, to all the line switches of the sub group. Therefore, the placing of ground potential on conductor 3 extends a ground potential to the similar conductor of each idle 35 line switch of the sub group, as each idle line switch has its release trunk conductor connected to the common guard conductor 39 in the same way as the trunk shown.

In order to maintain the guarding potential applied to conductor 39, the common relay 45 34 in the control group energizes over conductor 39 and locks ground on conductor 39 at its upper contacts through contacts of relays 32 and 33, the slow acting relay 33 being normally energized through contacts of relay 34. Relay 34 opens the circuit of the slow acting relay 33, but relay 33 remains operated for a substantial interval, the function of this relay being such that it is not required to fall back on every call, as it is provided for a special 55 condition to be hereinafter explained.

Responsive to the extension of the subscriber's loop to the line conductors 2 and 4, relay 5 whose upper winding is connected to conductor 2 energizes over the calling line 60 from the ground potential supplied to conductor 4 through the lower armature of relay 5. Upon operating, relay 5 locks itself to release trunk conductor 3 at its inner lower armature and it disconnects release-trunk conductor 3 from the common guard conduc-

tor 39 at its inner upper armature and closes a circuit from the grounded conductor 3 through the pull-down winding of the line switch magnet 7 to battery by way of the open-main conductor 38, through normally closed springs controlled by the plunger, the open main conductor being supplied with a battery potential through contacts of start relay 35 in the master switch. The plunger arm is operated in this manner and the 75 springs 8-11 are pushed into engagement with the corresponding contacts of the trunk line leading to the repeater R. As a further result of the operation of relay 5 it disconnects its upper winding and ground from conductors 2 and 4, and closes a circuit for the slow-releasing relay 6, which operates and prepares a guarding circuit for the trunk 80 line.

As a result of the extension of the connection to the repeater R, line relay 25 thereof operates over conductors 21 and 24 from the subscriber's loop and closes a circuit for release relay 26 which operates and places a ground potential on conductor 22 which extends back to release trunk conductor 3 of the secondary line switch so as to maintain the secondary line switch and the other apparatus of the connection, including the seizing selector, in an operated condition. As the further result of the operation of relay 25 of the repeater R, a bridge is placed across the outgoing conductors 27 and 28 including the right-hand repeating coil windings, preparing the switch (usually a selector) to which the trunk line extends in the distant office for operation in the usual manner.

As a result of the depression of spring 10 of the line switch SLS, when the line switch is operated as above described, a ground potential is placed on test conductor 23, rendering the trunk line busy to the master switch, with the result that start relay 35 of the master switch operates through test wiper 37 and closes a circuit at its lower armature for driving the master switch away from the busy trunk in search of an idle one. At its upper armature, relay 35 removes battery from the open-main conductor and places a ground potential thereon, closing a circuit for relay 31 of the common control group, which relay operates and closes a new locking circuit for relay 34 at its upper armature, at the same time operating relay 32 at its lower armature to open the initial locking circuit.

When the master switch finds an idle trunk as evidenced by the fact that no ground potential is encountered on the test conductor of such trunk line by test wiper 37, start relay 35 falls back and stops the operation of the master switch by opening its lower contacts. It removes the ground potential from the open main conductor 38 and replaces a 125 130

battery potential thereon, whereupon relay 31 of the common group falls back and removes the ground potential from the locking circuit of relay 34 and from the guard conductor 39, whereupon relay 34 falls back and opens a further point in its locking circuit, at the same time reclosing the circuit of the slow-acting relay 33, which relay is usually still in an operated condition unless a large number of trunks have been passed over during the test. Relay 31 also opens the circuit of relay 32, which falls back and again prepares the initial locking circuit of relay 34. The relative adjustment of relays 32 and 34 is such that relay 34 falls back and opens a further point in its locking circuit before relay 32 can fall back and reclose the initial locking circuit of relay 34.

The master switch has now selected another idle trunk line and the ground potential has been removed from the common conductor 39 so that other calls may be now handled through the said group. It will be understood of course, that the operation of preselecting another idle trunk and again rendering the sub group idle, takes place in a fraction of a second.

Further impulses transmitted from the calling telephone are repeated at the lower contacts of line relay 25 of the repeater R over conductors 27 and 28 to set the said switches in the distant office in the usual manner.

When the receiver is replaced on the calling telephone, relay 25 falls back and produces a prolonged opening of the circuit of slow-acting release relay 26, with the result relay 26 falls back and removes ground from the release-trunk conductor of the connection established in the local office at its upper armature, whereupon the seizing selector and other switching apparatus included in the connection release, and relay 5 of the secondary line switch SLS falls back. Upon so doing, relay 5, at its inner upper armature, closes a circuit through the operated armature of slow-acting relay 6 to ground, reapplying a guarding potential to conductor 3 so as to prevent a reseizure of the secondary switch during the restoration and realignment of the plunger thereof. After sufficient time is allowed for this operation the slow-acting relay 6 falls back, in response to its circuit being opened at the lower armature of relay 5, and reconnects the conductor 3 to the common guard conductor 39.

Referring again to the repeater R and to the master switch it will be noticed that there is a chain circuit for the stop relay 36 in the master switch including contacts of relay 26 and similar contacts of other relays such as 26' indicated above the repeater R. This contact chain is arranged to extend ground to stop relay 36 of the master switch only when all trunk lines accessible to the line switches

of the sub group are busy, merely to stop useless operation of the master switch and to save wear and tear on the mechanism and unnecessary drain on the exchange battery. The busy condition is maintained on a secondary group because test wiper 37 of the master switch does not encounter an unguarded test contact. Therefore relay 35 is maintained operated, with the result that relays 31 and 34 are maintained operated to maintain ground potential on guard conductor 39. 70 75

Regarding the utility of the slow acting relay 33, it may be pointed out that a ground potential is likely to be supplied accidentally to one of the release trunk conductors, such as the release trunk conductor 3 of the secondary line switch SLS, causing relay 34 to lock up and hold a busy condition on the entire sub group even after the original accidental ground potential has been removed. With the initial locking circuit of relay 34 controlled by slow acting relay 33, the circuit of which opened upon the operation of relay 34, the locking circuit of relay 34 and the busy circuit over conductor 39 is shortly opened removing the guarding potential from the release trunk conductor and permitting relay 34 to fall back again and reoperate relay 33 to again prepare the locking circuit of relay 34. 80 85 90 95

Referring now to Fig. 2 it will be apparent that the secondary line switch SLS' shown therein is similar in every respect except that no relay corresponding to relay 6 of Fig. 1 is provided and that the back contact of the inner upper armature of relay 5' leads directly to the common guard conductor instead of through contacts of a relay similar to relay 6 as in Fig. 1. This modification is for use of course wherever the self-aligning plungers are not required and therefore not used. 100 105

What is claimed is:

1. In a telephone trunking system, a plurality of incoming trunks each terminating in a preselecting switching mechanism, a lesser plurality of outgoing trunks accessible in common to all said mechanisms, means for making busy all idle incoming trunks when any incoming trunk is taken for use, means for thereafter operating the switching mechanism in which the seized trunk terminates, means common to all said preselecting switching mechanisms for preselecting another outgoing trunk, and means for maintaining the busy condition on the incoming trunks until said preselecting means has preselected another trunk. 110 115 120
2. In a telephone system wherein a plurality of non-numerical switching mechanisms are accessible to automatic switching apparatus, and are presided over by a master switch arranged to cause all idle non-numerical switching mechanisms controlled thereby to 125 130

preselect the same idle outgoing trunk, means responsive to the seizure of one of said non-numerical switching mechanisms for operating such mechanism to seize the idle pre-selected trunk and for operating the master switch to cause the remaining idle non-numerical switching mechanisms to preselect another idle trunk, and means for rendering artificially busy all idle switching mechanisms before the said seized mechanism is operated and for maintaining them busy to said automatic switching apparatus until the said operation of the master switch is performed.

3. In a telephone system wherein automatic switching apparatus has access to non-numerical switches governed by a master switch arranged to preselect an idle one of a plurality of trunks accessible to the non-numerical switches and to preselect another idle trunk when the preselected one is taken for use, means responsive to the seizure of one of said non-numerical switches for making all of them busy simultaneously and for maintaining the busy condition until the preselected trunk has been taken for use by the seized switch and the master switch has operated to preselect another trunk.

4. In a telephone system wherein automatic switching apparatus has access to non-numerical switches governed by a master switch arranged to preselect an idle one of a plurality of trunks accessible to the non-numerical switches and to preselect another idle trunk when the preselected one is taken for use, means responsive to the seizure of one of said non-numerical switches for making all of them busy and for maintaining the busy condition until the preselected trunk has been taken for use by the seized switch and the master switch has operated to preselect another trunk, said means including a self locking relay operated over the seized trunk line and unlocked responsive to the operation of the master switch.

45. 5. In a telephone trunking system, a plurality of trunks, means responsive to a seizure of one of said trunks for making all idle ones busy, and means including a progressively movable testing device common to said trunks for removing the busy condition from all of them that are idle.

6. In a telephone system, a plurality of incoming trunks, a plurality of outgoing trunks, switching mechanism for seizing incoming trunks, switching mechanism for connecting seized incoming trunks to idle outgoing trunks, and means common to said incoming trunks and controlled over any one of them for making all idle incoming trunks artificially busy whenever any one of them is seized.

65. 7. In a telephone system, a plurality of incoming trunks, a plurality of outgoing trunks, switching mechanism for seizing incoming trunks, switching mechanism for con-

necting seized incoming trunks to idle outgoing trunks, means common to said incoming trunks and controlled over any one of them for making all idle incoming trunks artificially busy whenever any one of them is seized, and means including a timing device common to all said incoming trunks for rendering idle the artificially busy trunks. 70

8. In a telephone system, a group of trunk lines, means common to said lines for placing an artificial busy condition on all idle trunk lines, and means including a timing device common to said trunk lines for removing the said artificial busy condition. 75

9. In a telephone trunking system, a plurality of incoming trunks each terminating in a preselecting switching mechanism, a lesser plurality of outgoing trunks accessible in common to all said mechanisms, means for making busy all idle incoming trunks when any incoming trunk is taken for use, means for thereafter operating the switching mechanism in which the seized trunk terminates, means for maintaining the busy condition on the incoming trunks until another trunk is 80 preselected, and means automatically effective to remove the busy condition at the end of a predetermined time in case the last-named switching mechanism fails to operate. 85

10. In a switching system, a line, an automatic switch arranged to extend said line, a line relay connected to said line and arranged to be energized thereover, an operating circuit for said switch controlled by said line relay, a release trunk conductor included in said line, a self-locking circuit for said line relay including said release trunk conductor, means external to said lineswitch for applying potential to said release trunk conductor before the lineswitch is operated 100 to prepare the said locking circuit for the line relay, and means external to said switch for removing the locking potential from said release trunk conductor when the connection set up through the switch is to be broken for deenergizing said line relay to permit said switch to release. 105

11. In a switching system, an incoming line terminating in a lineswitch, said line including a line conductor and a release conductor, means for applying potential to said release conductor and for operating said line relay in a circuit over the line conductor of said line, contacts on said line relay for closing a self-locking circuit for itself to said release conductor and for opening its line circuit, and additional contacts on said line relay for closing an operating circuit for said lineswitch. 115

12. In combination, a line incoming to a lineswitch arranged to extend the line, said line comprising a line conductor and a release conductor, means for applying a potential to said release conductor and for closing a circuit over the line conductor for said 120 125

line relay, and contacts on said line relay for closing a self-locking circuit over said release conductor, for opening its line circuit, and for closing an operating circuit for said 5 lineswitch over the release conductor.

13. In a switching system, an automatic switch, a line incoming to said switch including a line conductor and a release trunk conductor, means including a line relay in said

10 switch for operating the switch immediately responsive to current flow over the incoming line conductor, and means for maintaining said automatic switch operated responsive to further current flow over the incoming re-

15 lease trunk conductor.

14. In a switching system, a preselecting lineswitch accessible to an automatic switch by way of a trunk line including a line conductor and a release trunk conductor, means

20 for operating said automatic switch to extend a connection to the preselecting switch by way of said trunk line, means for operating the preselecting switch responsive to current flow over the line conductor of the

25 trunk line incoming thereto, and means for maintaining said preselecting switch operated by means of current flow over the release trunk conductor of the incoming trunk line.

30 15. In a switching system, a non-numerical automatic switch, a trunk line incoming to said switch comprising a line conductor and a release trunk conductor, means for extending a connection to said switch by way of the

35 said conductors of said trunk line and for setting up a current flow over the line conductor of the incoming trunk line and for applying a holding potential to the release trunk conductor of the incoming trunk line,

40 means in said non-numerical switch responsive only to current flow over both said incoming conductors for operating the non-numerical switch, and a circuit for holding said switch operated including the incoming

45 release trunk conductor of said trunk line.

16. In a switching system, a plunger lineswitch having access to a plurality of lines, means for preselecting one of said lines, a trunk line incoming to said switch having a

50 line conductor and a release conductor, means including an automatic switch for extending a connection to the lineswitch by way of said conductors, means for operating the lineswitch responsive to current flow over the

55 line conductor incoming thereto, and a holding circuit for both of said switches completed over said release trunk conductor.

17. In a switching system, a plurality of non-numerical switches having access to 60 trunk lines, a line incoming to each of said switches comprising a line conductor and a release conductor, a separate conductor multiplying all of said release conductors together, a line relay in each of said switches, 65 means for taking any one of said switches for

use over the incoming line thereof and for setting up a current flow over the line conductor of the incoming line, said line relay being responsive to said current flow, and contacts on said line relay for closing an operating circuit for the switch and for disconnecting the release conductor of the associated incoming line from the common conductor:

18. In a switching system, a plurality of 70 trunk lines accessible to an automatic switch, each of said trunk lines including a line conductor and a release conductor, connections multiplying all of said release conductors together, a line relay in each of said trunk 80 lines responsive to current flow over the associated line conductor when the trunk line is taken for use by said automatic switch, and contacts on said line relay for disconnecting the associated release conductor from 85 the common conductor.

19. In a switching system, a plurality of 90 automatic switches, a separate trunk line incoming to each switch, each trunk line including a line conductor and a release conductor, all of said release conductors being normally connected together so that the application of guarding potential to one of them results in an application of guarding potential to all of them, means for taking any one of 95 said trunk lines for use, means responsive thereto for operating the switch in which the seized line terminates and for disconnecting the associated release conductor from the other release conductors and for closing a holding circuit for the associated switch over the release conductor, means for subsequently opening the holding circuit to permit the operated switch to release, and means responsive thereto for applying a guarding potential to 100 said release conductor.

20. In a switching system, a plurality of 110 automatic switches, a separate trunk line incoming to each switch, each trunk line including a line conductor and a release conductor, all of said release conductors being normally connected together so that the application of guarding potential to one of them results in an application of guarding potential to all of them, means for taking any one 115 of said trunk lines for use, means responsive thereto for operating the switch in which the seized line terminates and for disconnecting the associated release conductor from the other release conductors and for closing a holding circuit for the associated switch over the release conductor, means for subsequently opening the holding circuit to permit the operated switch to release, and means responsive 120

125 to applying a guarding potential to said release conductor, and means for subsequently removing said guarding potential and for reconnecting said release conductor to the release conductors of the other trunk lines.

21. In a non-numerical switch having a line conductor and a release conductor incoming thereto, a line relay operative over the line conductor, and an operating circuit for said switch including said release conductor and closed responsive to the energization of the line relay.
22. In combination, a non-numerical switch, a line conductor and a release trunk conductor incoming thereto from a preceding automatic switch, and a magnet responsive to operate said non-numerical switch depending upon the closure of a line circuit over the incoming line and the application of a potential to said release-trunk conductor when the said preceding switch is operated.
23. In a telephone system, a line, an automatic switch and means for controlling the same to extend said line to an idle trunk line, a preselecting secondary plunger lineswitch terminating said trunk line, means controlled over a talking conductor of said trunk line for operating said lineswitch when the trunk line is seized by said first switch, a release trunk conductor extending between said switches, means in said automatic switch for applying potential momentarily to said release trunk conductor and for removing it after an interval, and means controlled through said secondary switch for applying potential to said release trunk conductor for maintaining the first switch in operated position after the potential has been removed from the said release trunk conductor at said automatic switch.

In witness whereof, I hereunto subscribe my name this 13th day of June, A. D. 1928.

JOHN I. BELLAMY.
